Primary Examiner — Sanjeev Paul

(74) Attorney, Agent, or Firm — ALLEN, DYER ET AL.

(57) **CLAIM**

The ornamental design for a contact lens inserter, as shown and described.

DESCRIPTION

FIG. 1 is a top perspective view of a contact lens inserter showing my new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

1 Claim, 7 Drawing Sheets
